UNITED STATES PATENT OFFICE.

FREDERICK E. STROHMEIER, OF ASHLAND, PENNSYLVANIA.

ORNAMENTAL HAND-WOVEN FABRIC AND METHOD OF MAKING THE SAME.

Application filed December 4, 1922. Serial No. 604,776.

To all whom it may concern:

Be it known that I, FREDERICK E. STROHMEIER, a citizen of the United States, residing at Ashland, in the county of Schuylkill and State of Pennsylvania, have invented certain new and useful Improvements in Ornamental Hand-Woven Fabrics and Methods of Making the Same, of which the following is a specification, reference being had to the accompanying drawings.

This invention relates to fabrics and methods of making the same, and particularly to the method of making a fabric, which method is particularly adapted for use in making sweaters, scarfs, afghans and the like.

One of the objects of this invention is to provide a method whereby an article may be made very quickly and simply by relatively unskilled persons and yet very brilliant and attractive effects may be secured. Furthermore, the method includes the use of a base or foundation fabric which has itself an ornamental design and which foundation fabric becomes an inevitable part of the color scheme and design of the completed article.

A further object of the invention is to construct the woven fabric on a base or foundation of another woven fabric, this base or foundation fabric being so formed as not only to form an ornamental and integral part of the completed fabric but so formed as to permit of very wide variations in treatment being used and permitting of very decorative effects being secured by very simple means.

Other objects will appear in the course of the following description.

My invention is illustrated in the accompanying drawings, wherein:—

Figure 1 illustrates a fragment of the base or foundation fabric;

Figure 2 is a face view showing diagrammatically the manner in which colored wools are woven in and out by hand through the meshes of the base or foundation fabric;

Figure 3 is a fragmentary view of a portion of a scarf or like article which has been woven in accordance with my invention;

Figure 4 is a face view of the blank or foundation fabric used in making a sweater or like article;

Referring particularly to Figure 1, it will be seen that the foundation fabric 10 consists of net so woven as to provide a

series of open knots 11 spaced from each other, the knots being connected by strands 12 so that the knots 11 are located at the four corners of an approximately square opening 13. The knots 11 are so formed as to leave a central opening 14 in each knot.

In constructing any article as, for instance, a scarf, sweater or the like, a piece of the foundation fabric 10 is taken of sufficient length and breadth to form the complete article, and woolen yarn of sufficient weight and designated 15 is woven back and forth over and under the connecting strands 12 and through the openings 13 from one edge of the blank of foundation fabric to the other until the entire fabric to any desired degree has been filled with the yarn. This yarn is relatively heavy so that the strands of yarn will practically fill up the openings 13 and will partly overlie the knots 11.

In Figure 2 I show a fabric wherein a line of the openings or spaces 13 has been filled up by three strands of yarn. For instance, the yarn 15 is doubled, as illustrated, and carried in and out across the fabric over one connecting strand 12, beneath the next adjacent connecting strand, then over the next connecting strand and under the next, and so on across the entire width of the fabric. The yarn may be doubled, as illustrated in Figure 2, and thus woven in and out through the fabric 10 and then a third strand, designated 15^a, is woven backward and forward through the fabric between the strands 15 and reversely to the strands 15, that is where the strands 15 pass beneath a connecting portion 12 the strand 15^a passes over this connecting portion. This weaving in and out may be done by the use of a bodkin or any other instrument of the same character and designated in the drawing A.

Obviously more than three strands of wool may be woven in and out through the spaces 10 if desired. Obviously the strands 15 might be of wool of one color and the strand 15^a of wool of another color, or both the strands 15 and 15^a might be of the same color, or the double strand 15 might be of two different colors and the strand 15^a of still another color. Furthermore, it is obvious that instead of passing alternately above and below the connecting portions 12 of the fabric 10, the strands 15 and 15^a might pass over two of the strands 10 and then beneath one or two strands and then again

over two and so on. Thus a great variety of different weaves may be used upon this foundation.

In Figure 3 I have illustrated the completed fabric, and it will be noted that the knots, as I have termed them, 11 form an integral part of the design and thus if the foundation fabric is of contrasting color to the wools which are used therewith, the completed fabric will present a very complicated appearance, as if it had required great skill to weave it. I have illustrated in Figure 3 also that, for instance, in forming a scarf or any other article the ends of the strands 15 and 15^a may be tied, as at 16, at the borders of the fabric and the ends of the strands be left free, as at 17, to form a fringe or other finish for the garment. Obviously strands of wool to form a fringe 20 may be tied into the fabric 10, this fringe being of a wool of a different color from the wool which is used to form the body portion of the completed fabric.

The maker of the fabric may leave the knots 11 to show so that these knots form an ornamental part of the pattern, and this is a preferable method of forming the fabric, but it is obvious that strands 18, as illustrated in Figure 3, might be woven at intervals through the openings 14 of the knots 11 in and out in precisely the same way that the strands 15 or 15^a are woven in and out of the opening 13, and these strands 18 might be of a color contrasting strongly 35 with the strands 15 or 15^a. These strands 18 might be woven at right angles to the strands 15 or 15^a so as to cross over on the exterior of the fabric. Any number of strands may be used for each course of openings 13. It will be noted that if three strands are used an appearance of a chain 40 stitch is formed which is found very attractive.

In Figure 4 I have illustrated the blank 45 formed of the fabric 10 and which constitutes the foundation for a sweater. This blank B is preferably made of one piece with a central opening b for the neck. After the yarn has been woven through the meshes 50 of the blank B the blank is folded upon itself and stitched along the side edges b' in an obvious manner. Obviously the blank may be formed to provide a sweater having short sleeves, long sleeves or no sleeves, and the 55 neck may be formed in any desired fashion. Preferably in weaving as long a strand of yarn is used as is possible. Where sections are to be pieced, one section of the foundation fabric is laid upon the other section and 60 then the yarn woven through the two sections. At the edges of the sweater the foundation fabric may be doubled back for two or three meshes and then the yarn woven through in the same manner as 65 through a single thickness of net. When

the weaving is finished the collars and cuffs, which may be made by crocheting or in any other suitable manner, are stitched to the completed sweater or other garment on the sewing machine. Collars and cuffs may be 70 knitted in the usual manner, crocheted or otherwise formed for application to the completed garment.

Garments or other articles formed as described by my method and with the foundation fabric illustrated in Figure 1 are capable of great variations in design and the effect is particularly rich and beautiful. The work obviously may be very easily done and requires but a minimum of time. 75

It will be understood, of course, that the net foundation may have any desired color with which the colors of the worsted or yarn used will contrast or blend so that, as before stated, the net not only forms a foundation upon which the yarn is carried but a part of the total color scheme and design of the article which is being made. 80

While I have illustrated a particular form of net foundation 10, I do not wish to be limited to this particular form, though the particular foundation used is of great value because of the fact that the knots occurring at the intersection of the longitudinal and transverse strands of the fabric form an integral part of the design itself and add very greatly to the richness and beauty of the design, while at the same time the central openings in these knots permit of the use of auxiliary strands 18 either extending transversely or longitudinally of the fabric or diagonally thereof, which enhance the richness and beauty of the fabric. 95

While I have heretofore referred to the use of woolen yarns, it is to be understood that the term "yarn" is used to include silk, woolen or cotton yarns. 105

I claim:—

1. A method of forming a fabric which consists in using a relatively coarse open mesh net as a foundation, said net having longitudinal and transverse strands and open knots at the intersection of the longitudinal and transverse strands, and weaving strands of yarn in and out through the meshes of the foundation net until said meshes have been filled with yarn whereby to form a complete fabric wherein the knots constitute an integral part of the design. 110

2. A method of forming a fabric which consists in using as a foundation a relatively coarse open mesh net having longitudinal and transverse strands and substantially annular knots at the intersections of the longitudinal and transverse strands, and weaving strands of yarn in and out parallel to each other through the meshes of the foundation net until said meshes have been filled with yarn, and weaving yarn in and out through the openings in said knots. 120

3. A fabric comprising a foundation of relatively large open mesh net having longitudinal and transverse strands and substantially annular knots at the intersection 5 of the transverse and longitudinal strands, and a filling of yarn woven through the meshes of the net.
4. A fabric comprising a foundation of relatively large open mesh net having longitudinal and transverse strands and annular knots at the intersection of the transverse and longitudinal strands, the spaces between said knots being filled with strands 10 of yarn extending in the same direction and woven in and out over and under the strands of the net, certain of the strands of yarn being woven reversely to the remainder of the strands of yarn, said meshes being thereby filled with yarn to thereby form a fabric
- wherein the knots constitute an integral 20 part of the design.
5. A fabric comprising a foundation of relatively large mesh net having longitudinal and transverse strands and substantially annular knots at the intersection of the 25 transverse and longitudinal strands, and a filling of yarn of different color from the color of the net woven back and forth through the meshes of the net and filling said meshes, the knots constituting an integral 30 part of the design, the strands of yarn extending in the same direction but certain of the strands being woven reversely to certain other strands to produce an ornamental pattern. 35

In testimony whereof I hereunto affix my signature.

FREDERICK E. STROHMEIER.
